SIGNAL LIGHT SUPPORTING BRACKET

Roger G. Young, Rochester, N.Y., assignor of
forty percent to Uniweld, Inc.

Filed May 4, 1964, Ser. No. 79,790

Term of patent 7 years

(Cl. D72—1)

FIG. 1

FIG. 2

FIG. 3

FIG. 4

FIG. 1 is a front elevational view of a signal light supporting bracket showing my new design, the side opposite that shown being substantially a mirror image thereof;

FIG. 2 is a top plan view thereof;

FIG. 3 is a left-end elevation thereof as seen in FIG. 1; and

FIG. 4 is a right end elevation thereof as seen in FIG. 1.

The essential features of my design reside in the solid line portions. The broken line showing of a portion of a support pole and two signal lights in FIG. 1 is for illustrative purposes only.

I claim:

The ornamental design for a signal light supporting bracket, substantially as shown and described.
